FREDERICK M. VENZIE, OF PHILADELPHIA, PENNSYLVANIA

BUILDING STRUCTURE

Application filed February 18, 1929. Serial No. 340,862.

This invention, generally stated, relates to a building construction and has more particular relation to a wall or partition structure wherein plaster boards are employed.

5 The leading object of the present invention is to provide a construction of the character stated in which simplicity of construction is provided, erection costs reduced, rigidity of structure attained, and general efficiency enhanced.

10 A further object is to provide a wall or partition construction which may be erected by unskilled labor in quicker time, at less expense and more efficiently than skilled mechanics now erect commercial wall board.

15 Other and further objects of the present invention reside in the provision of general details of construction and arrangement of parts for attaining the results sought by the foregoing objects.

The invention consists of the novel construction hereinafter described and finally claimed.

20 The nature, characteristic features and scope of the invention will be more fully understood from the following description taken in connection with the accompanying drawings forming part hereof, and in which:

Fig. 1, is a fragmentary view in elevation 30 of a wall or partition structure embodying the invention.

Fig. 2, is a view in elevation showing a detail of construction.

Fig. 3, is a similar view illustrating a detail of construction.

Fig. 4, is a view in section taken upon the line 4—4 of Fig. 2.

Fig. 5, is a view in section taken upon the line 5—5 of Fig. 2; and

40 Fig. 6, is a view in perspective illustrating one of the clips shown in the foregoing figures.

For the purpose of illustrating my invention I have shown in the accompanying drawings one form thereof which is at present preferred by me, since the same has been found in practice to give satisfactory and reliable results, although it is to be understood that the various instrumentalities of 45 which my invention consists can be variously

arranged and organized and that my invention is not limited to the precise arrangement and organization of the instrumentalities as herein shown and described.

Referring to the drawings in detail, the 55 reference numeral 10 designates sections of plaster board as "Rockwall" or any of the other well known commercial makers. These sections or slabs of plaster board 10 are erected upon studding 11 and nailed thereto. 60 However, practice dictates that stability of the slabs may be materially increased by the employment of the attachments of the present invention, a description of which follows:

As the slabs 10 are nailed to the studding 65 11 many of the slabs have their ends unsupported. This makes for a very inefficient structure to support the plaster thereafter to be applied. Therefore, I propose to leave between adjacent wall slabs spaces sufficient to 70 accept the devices forming part of the invention.

First I use a U-shaped, staple-like member, best seen in Fig. 4 and which is designated 12. This member 12 I drive into a pair 75 of adjacent slabs 10 which may be readily done because the slabs are of relatively soft material. The member 12 is provided with a depressed portion 13 to accept a clip 14 about to be described. This clip 14 may be 80 best seen in Fig. 6 and like the member 12 is made of wire. The member 14 is bent to provide a cross piece 15 extended from which at right angles thereto is a short section 16, extended from which at an inclination thereto is an arm 17 terminating in a finger 18. In practice the cross piece 15 is introduced to a slot 19 between adjacent slabs 10, as shown in dotted lines in Fig. 2. The cross piece is then shifted so that the 90 cross piece 15 extends across the slot 19 instead of in parallelism therewith and the arm 17 is forced down over the member 12 so that the part 16 abuts against the member 12 and clamps the parts securely together with the 95 arm 17 paralleling the slot 19. This arrangement of parts is very clearly seen in Fig. 5. It is apparent that with a plurality of these members 12 and clamps 14 used between adjacent slabs, as is best seen in Fig. 1, stability 100

of the slabs is secured. It is also apparent that these devices are so simple and so easily applied that unskilled labor may readily position them. It will be understood, of course, 5 that with the slabs 10 in position and the various clips in position the usual plaster is placed over the wall or partition, although the plaster is not shown in the drawing. Between the parts 16 and 17 of the clamp there 10 is provided a curved portion 20 which fits over the depression 13 of member 12 and adds to the efficiency in the interlocking of parts.

Having thus described my invention, what 15 I claim is:

15 1. A building structure comprising a plurality of wall slabs suitably supported, adjacent slabs having free spaces therebetween, staple-like members driven into a pair of 20 slabs and arranged across said free spaces, clamping clips having cross members arranged across said free spaces upon the faces of the slabs opposite said staple-like members, and arms extended from said cross 25 members and clamped over said staple-like members, said arms being arranged within said free spaces and in parallelism therewith.

2. A structure as described in claim 1 30 characterized by said staple-like member being formed of wire and having a central depressed portion to be engaged by the arm of the clamping member.

3. A structure as described in claim 1, 35 characterized by the clamping clip being formed of wire in one piece bent to form the cross-piece which has extended at right angles thereto a short section which terminates in an arm disposed in the same plane 40 with said short section and having a curved part between said short section and arm for engaging over the staple-like member.

FREDERICK M. VENZIE.
